UNITED STATES PATENT OFFICE.

MICHAEL HENRY, OF TERRE HAUTE, INDIANA.

SCISSORS-SHARPENER.

No. 883,019.

Specification of Letters Patent. Patented March 24, 1908.

Application filed December 17, 1907. Serial No. 406,914.

To all whom it may concern:

Be it known that I, MICHAEL HENRY, citizen of the United States, residing at Terre Haute, in the county of Vigo and State of Indiana, have invented new and useful Improvements in Scissors-Sharpener, of which the following is a specification.

My invention pertains to devices for sharpening scissors and other edge tools; and it 10 contemplates the provision of a simple and inexpensive device through the medium of which scissors may be expeditiously sharpened in a correct manner with but a minimum amount of effort and without entailing 15 the employment of skilled labor.

The novelty, utility and practical advantages of the invention will be fully understood from the following description and claims when the same are read in connection 20 with the drawings, accompanying and forming part of this specification, in which:

Figure 1 is a perspective view illustrating the device constituting the best known embodiment of my invention and also illustrating 25 a pair of scissors as properly fastened in the device and positioned to be sharpened. Fig. 2 is a vertical section, on a slightly enlarged scale, illustrative of the arrangement of the rotatable upright of my device in the 30 fixed sleeve by which the same is supported. Fig. 3 is a detail view partly in section and partly in elevation, showing the novel clamp of my improved device. Fig. 4 is a detail plan of the tool-holding clamp.

Similar letters designate corresponding parts in all of the views of the drawings, referring to which:

A is a support which may be a table or the like.

B is the base of my improved sharpening device, and C is a clamp which is illustrated as one means through the medium of which the base may be fixedly secured on a table or other support. While I prefer to have my 45 novel device comprise a base such as just described, of hardwood or other suitable material, I desire it understood that without involving departure from the scope of my invention as claimed, the base may be formed

50 by a table top or may be of any other character compatible with the purpose of my invention.

Fixed in a recess *a* of the base B is a stone or other suitable abrasive medium D, and in 55 addition to the base B and the abrasive me-

dium D my novel device comprises a tubular upright E fixed to the base B at about the distance shown from the abrasive medium, a rotatable upright F having its lower portion disposed in the said tubular upright E 60 and equipped with a collar *b* which is fixed to it by a set screw *c* or other suitable means, and is designed to bear and turn on the upper end of the upright E, a guide rod G pivoted at *d* to the upper portion of the rotatable 65 upright F and arranged to swing vertically, a sleeve H receiving and movable rectilinearly in opposite directions on the guide rod H and having depending clamping members I and a bolt J extending through the same 70 and a wing nut K mounted on said bolt and arranged to crowd the members I toward each other, an arm L, preferably of twisted sheet-metal having its upper vertically disposed portion *e* disposed between the clamping members I and mounted to swing vertically on the bolt J, a scissors-engaging clamping member M arranged to coöperate with a complementary clamping member formed by the lower portion of the arm L, and a bolt P 80 and wing or other suitable nut arranged to coöperate with the said clamping members M and N to fasten a pair of scissors to the sharpening device. I prefer in the manufacture of my improved device to form the 85 clamping members I of a single piece of sheet-metal which straddles and is curved in conformity to the sleeve H and is brazed thereto.

As clearly illustrated in Figs. 1 and 3, the clamping member N formed by the lower 90 portion of the arm L is provided with an upward swell or raised portion *e'*, a forward shoulder *f* disposed at an acute angle to the longitudinal median line of the arm L, and a lip *g* reaching forward from the shoulder *f* 95 and having its forward edge arranged parallel to the said shoulder. It will also be seen by reference to Figs. 1 and 3, that the upper clamping member M has a rear flange *h* and a forward flange *i*; the said flange *i* 100 being disposed at an acute angle to the longitudinal median line of the arm L so as to enable its lower edge to bear on the lip *g* throughout the length thereof.

The scissors to be sharpened are arranged 105 in my novel device in the manner illustrated in Fig. 1—that is to say, one blade of the scissors is arranged on the lip *g* with the rear edge of the blade bearing against the shoulder *f* of clamping member N, and the 110

blade is clamped and securely held against the said lip *g* by the forward flange *i* of the upper clamping member *M*. At this point it will be noted that by reason of the shoulder *f* of the clamping member *N* being disposed at an acute angle to the longitudinal median line of the arm *L*, the scissors blade is positioned at an acute angle to the line in which the sleeve *H* is reciprocated or moved rectilinearly with the result that the said blade will be moved over the abrasive medium *D* while positioned at an acute angle to the line of movement. This conduces to the expeditious and proper sharpening of the blade, and is advantageous for that reason.

In the practical operation of my device, the scissors are arranged with one blade on the abrasive medium *D* and in the clamp on the arm *L*, and the operator then grasps the scissors and moves the blade thereof over the abrasive medium until the said blade is sharpened to the extent desired. In this connection it will be noticed that during the sharpening operation, the pivotal connection *d* enables the operator to press the blade as necessary against the abrasive medium, while the rotatable upright *F* permits of the blade being freely moved in the direction of its length to and fro over the abrasive medium, and the sleeve *H* movable rectilinearly on the guide rod *G* permits of the blade being moved to and fro over the abrasive medium in the direction of the width of the blade. These several movements of the blade relative to the abrasive medium *D* facilitate the proper sharpening of the blade with the result that such sharpening is quickly accomplished and with the expenditure of but a minimum amount of effort. The arm *L* is preferably connected with the reciprocatory sleeve *H* in the adjustable manner described in order that said arm may be adjusted and adjustably fixed in order to properly dispose the blades of scissors of different sizes to the stone or abrasive medium *D*.

In addition to the practical advantages hereinbefore ascribed to my novel scissors sharpener, it will be appreciated that the said sharpener is simple and inexpensive in construction, and is well adapted to withstand the hard usage to which devices of corresponding character are ordinarily subjected.

I have entered into a detailed description of the best embodiment of my invention of which I am cognizant, in order to impart a full, clear and exact understanding of the said embodiment, but it is obvious that in the future practice of the invention such changes or modifications may be made as fairly fall within the scope of my invention as defined in the appended claims.

Having described my invention, what I

claim and desire to secure by Letters-Patent, is:

1. A device for sharpening scissors and other edge tools, comprising an abrasive medium, an upright mounted to rotate about its axis and fixed with respect to the abrasive medium, a guide pivotally connected with the said upright and arranged to be moved up and down thereon, and means for holding the tool to be sharpened; the said means being carried by and movable rectilinearly on the said guide.

2. A device for sharpening scissors and other edge tools, comprising an abrasive medium, an upright fixed with respect to the abrasive medium and mounted to turn about its axis, a guide pivotally connected with the said upright and arranged to swing vertically, means carried by and movable rectilinearly on the said guide, an arm connected with and extending downward and forward relative to said means and terminating at its lower and forward end in a clamping member having a shoulder disposed at an acute angle to the line of movement of said means and also having a lip reaching forward from the said shoulder, a clamping member disposed on the first mentioned member and having a forward depending flange disposed at an acute angle to the line of movement of said means and arranged to coöperate with the lip of the lower clamping member, and means for crowding the said clamping members against a tool.

3. A device for sharpening scissors and other edge tools, comprising a base, an abrasive medium carried thereby, means connected with the base and guided to move rectilinearly with respect to the base and the abrasive medium, a clamping member connected with the said means and having a shoulder disposed at an acute angle to the line of movement of said means and also having a lip reaching forward from the said shoulder, a clamping member disposed on the first mentioned member and having a forward depending flange disposed at an acute angle to the line of movement of the said means and arranged to coöperate with the lip of the lower clamping member, and means adjustably connecting the said members.

4. A device for sharpening scissors and other edge tools, comprising a base, an abrasive medium fixed to and carried thereby; an upright mounted to rotate about its axis on the base and fixed with respect to the abrasive medium, a guide rod pivotally connected with the said upright and arranged to swing vertically, a sleeve movable rectilinearly on said rod, and means for holding the tool to be sharpened, carried by and movable with the said sleeve.

5. A device for sharpening scissors and other edge tools, comprising a base, an abrasive medium fixed to and carried by the base,

an upright fixed with respect to the abrasive medium and mounted to rotate about its axis on the base, a guide rod pivotally connected with the said upright and arranged to swing vertically, a sleeve movable rectilinearly on said guide rod and having depending clamping members, and also having a bolt extending through said clamping members and a nut on the bolt, and an arm mounted on the bolt between the said clamping members and provided with means for holding the tool to be sharpened.

5 having depending clamping members, and also having a bolt extending through said clamping members and a nut on the bolt, an arm mounted on said bolt and between the clamping members and extending downward 25 and forward therefrom and terminating at its forward end in a clamping member, a clamping member arranged on the said clamping member of the arm, and a bolt and a nut on the bolt for crowding the last mentioned clamping member against the clamping member of the arm.

20

6. A device for sharpening scissors and other edge tools, comprising a base, an abrasive medium fixed on the base, a tubular upright fixed to the base, an upright supported in said tubular upright and arranged to turn about its axis, a vertically swinging guide rod connected to said rotary upright, a sleeve movable to and fro on said guide rod and

having depending clamping members, and also having a bolt extending through said members and a nut on the bolt, an arm mounted on said bolt and between the clamping members and extending downward 25 and forward therefrom and terminating at its forward end in a clamping member, a clamping member arranged on the said clamping member of the arm, and a bolt and a nut on the bolt for crowding the last mentioned clamping member against the clamping member of the arm.

30

In testimony whereof I have hereunto set my hand in presence of two subscribing witnesses.

MICHAEL HENRY.
